UNITED STATES PATENT OFFICE

121,582

DESIGN FOR A VOTIVE LIGHT HOLDER

Ottolie Amend, New York, N. Y., assignor to herself and Francis Gilpin-Brown, New York, N. Y., jointly

Application May 6, 1940, Serial No. 92,190

Term of patent 3½ years

To all whom it may concern:

Be it known that I, Ottolie Amend, a citizen of the United States of America, residing at New York city, county of New York, and State of New York, have invented a new, original, and ornamental Design for a Votive Light Holder, of which the following is a specification, reference being had to the accompanying drawing, forming part thereof, wherein—

Fig. 1 is a top plan view of the votive light holder showing my new design;

Fig. 2 is a front elevational view of the same.

I claim:

The ornamental design for a votive light holder, substantially as shown.

OTTILIE AMEND.
